DESIGN FOR A TEXTILE FABRIC OR SIMILAR ARTICLE

John J. Maibach, New York, N. Y., assignor to Davis & Catterall, New York, N. Y.

Application March 13, 1935, Serial No. 55,865

Term of patent 3½ years

To all whom it may concern:

Be it known that I, John J. Maibach, a citizen of the United States of America, residing at New York city, New York, have invented a new, original, and ornamental Design for a Textile Fabric or Similar Article, of which the following is a specification, reference being had to the accompanying drawing, forming a part thereof.

The figure is a plan view of a textile fabric showing between the dot and dash lines one complete unit of my new design.

I claim:

The ornamental design for a textile fabric or similar article as shown and described.

In testimony whereof I have signed this specification.

JOHN J. MAIBACH.
